CLAIM

The ornamental design for an apparel hood, as shown and described.

DESCRIPTION

FIG. 1 is a front-side perspective view of an apparel hood showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line portions of the drawing figures are included to show unclaimed subject matter only and form no part of the claimed design. In particular, the text circumscribing the face opening of the hood forms no part of the claimed invention.
